US00D820239S

(12) **United States Design Patent** (10) **Patent No.:** **US D820,239 S**
(45) **Date of Patent:** **** Jun. 12, 2018**

(54) **EARPHONE**

- (71) Applicant: **JVC KENWOOD Corporation**, Yokohama-shi, Kanagawa (JP)
- (72) Inventors: **Satoshi Yoshimura**, Kanagawaku Yokohamasi Kanagawaken (JP); **Takuya Arimoto**, Kanagawaku Yokohamasi Kanagawaken (JP); **Yui Ando**, Kanagawaku Yokohamasi Kanagawaken (JP); **Takaaki Maeda**, Kanagawaku Yokohamasi Kanagawaken (JP)
- (73) Assignee: **JVC KENWOOD Corporation**, Yokohama-shi, Kanagawa (JP)

(**) Term: **15 Years**

(21) Appl. No.: **29/593,554**

(22) Filed: **Feb. 9, 2017**

(30) **Foreign Application Priority Data**

- Aug. 31, 2016 (JP) D2016-018682
- (51) LOC (11) Cl. **14-01**
- (52) U.S. Cl. ..... USPC **D14/223**
- (58) **Field of Classification Search**
USPC D14/223, 205; 181/129, 130, 135; 379/430, 431; 381/380, 381, 330, 322, 381/370; 455/90.3, 575.1, 569.1
CPC H04R 1/10; H04R 25/00; H04R 25/02; H04R 1/1066; H04R 1/1016

(57) **CLAIM**

The ornamental design for an earphone, as shown and described.

DESCRIPTION

FIG. 1 is a front perspective view of an earphone.

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a right side view of FIG. 1; and,

FIG. 7 is a left side view of FIG. 1.

The broken lines in the drawings adjacent the shaded areas represent an unclaimed seam while all other broken lines are directed to environment and are for illustrative purposes only; the broken lines form no part of the claimed design.

1 Claim, 7 Drawing Sheets
